INDIRECT LIGHTING LUMINAIRE

Leroy C. Doane, Meriden, Conn., assignor to The
Sight Light Corporation, Essex, Conn., a cor-
poration of Connecticut

Application December 21, 1938, Serial No. 246,943

6 Claims. (Cl. 240—73)

The present invention relates to indirect lighting luminaires, and is more particularly directed toward luminaires adapted to be used below the normal eye level for illuminating a working plane 5 below the luminaire, and wherein the light source is in the form of a lamp carried in a substantially horizontal lamp socket.

The present invention contemplates a luminaire for the above purposes wherein the lamp is received in a pocket which reflects light upwardly and outwardly, and wherein the lamp is placed close to and below an opaque reflecting cover which screens the lamp against observation at normal eye level and reflects light downwardly and outwardly, the luminaire being provided with screening means between the edges of the pocket and of the cover for intercepting light emitted by the lamp at angles below the cover. In order that the vertical depth of the light controlling 15 elements may be small, and in order that there will be the minimum obstruction to the downwardly emitted light, the pocket is made just large enough to receive the lamp bulb (which may be of the 40 or 60 watt size), and means is provided whereby the lamp bulb and socket can be swung upwardly to permit removal of the lamp bulb.

The present invention also contemplates a spring mounting for the lamp bulb socket and lamp bulb of a luminaire so that the bulb and socket may be shifted from normal position.

The accompanying drawing shows, for purposes of illustrating the present invention, one of the many embodiments in which the invention 30 may take form, together with a modification of certain parts, it being understood that the drawing is illustrative of the invention rather than limiting the same.

In the drawing:

40 Figure 1 is a top plan view of a luminaire with parts broken away to show interior construction;

Figure 2 is a longitudinal sectional view on the line 2—2 of Figure 1;

Figure 3 is a transverse sectional view on the line 3—3 of Figure 2;

Figure 4 is a fragmentary sectional view showing the lamp socket in elevated position and illustrating a modified form of holder for the socket support; and

50 Figure 5 is a fragmentary section taken on the line 5—5 of Figure 3 at an enlarged scale.

In the form of construction shown in Figures 1 to 3, inclusive, the luminaire is supported on a tubular arm 10 which is threaded into a housing member 11. This housing member carries a

switch indicated at 13 and is adapted to receive screws 14 and 15 for securement of a pocket-forming member 16 in place. The pocket-forming member is apertured as indicated at 17 to accommodate wires, and has an upwardly opening wireway 18. The sides 19 and 20 of the wireway are notched as indicated at 21 to receive the ends 22 of a bent member 23. These ends are held down by spring fingers 24a and 24b formed in plate 24. The plate is secured in place by screws 10 25 and has an upstruck stop member 26 for a purpose to be described.

The member 23 is bowed, as indicated in the drawing, and the other end 27 is secured to a lamp socket 28 having its axis substantially horizontal and adapted to support a lamp bulb 29 as indicated. The pocket-forming member 16 extends out under the lamp socket and under the lamp bulb and is preferably made to be very close to the lamp bulb. The spring fingers 24a and 24b 20 act to hold the lamp socket and bulb in the position shown in full lines in Figure 2, and when one wishes to remove the lamp or to insert a new lamp, the lamp (or the lamp and socket) are lifted up to the position in Figure 4 to bring the 25 bowed member 23 against the abutment 26 and bend the spring fingers.

The pocket-forming member 16 is provided with three outwardly extending arms 30 which carry an annular downwardly and outwardly 30 flared screen 31. The screen, the arms and the entire pocket member may be made of a single die-casting, if desired, or may be made up from a number of separate pieces. The screening means 31 supports three posts 32 and these posts 35 detachably support an opaque reflecting cover 33 whose central portion preferably is brought down close to the upper surface of the lamp bulb and whose periphery is substantially in the plane of the top of the screening means 31. The diameter 40 of the cover 33 is such as to cover and conceal the lamp, the lamp socket and the socket support.

With the parts shown in the drawing it is apparent that the lower pocket 16 acts as a reflector for the downwardly emitted light and reflects this light up on to the upper cover. The upper cover receives the direct and reflected light and directs it out through the space between the screen and the edge of the cover, some of the light is directed down between the screen and the edge of the pocket and the screen also receives some light from the luminous upper surface of the bulb so that the light is utilized in the very efficient manner to produce a high luminosity on the working surface at consider- 50 55

able distances from nadir, as well as sufficient light directly below the luminaire.

In the arrangement shown in Figure 4, the switch housing is omitted and the tubular supporting arm 40 is threaded directly into the pocket-forming member.

It is obvious that the invention may be embodied in many forms and constructions within the scope of the claims and I wish it to be understood that the particular form shown is but one of the many forms. Various modifications and changes being possible, I do not otherwise limit myself in any way with respect thereto.

What is claimed is:

15. 1. In a luminaire, a lamp bulb, a lamp socket, a socket support having lateral extensions at the free end, a pocket forming member adapted to receive the bulb and socket and having notches to receive said extensions, and springs bearing on the extensions to yieldingly hold the socket and bulb in the pocket forming member and permit swinging them partially outwardly.
20. 2. In a luminaire, a tubular arm, a housing member secured to the end of the arm, the housing member having a chamber to accommodate wiring and a switch, a socket receptacle closing the wiring chamber and apertured for wiring, and a socket pivotally secured to the socket receptacle to swing up and down, the socket receptacle having upwardly extending walls, and a spring secured to the walls to be yieldable up and down, and acting on the socket support to hold the socket in its lower position.
25. 3. A luminaire, for use below the normal eye level and for illuminating a working plane below the luminaire, comprising a substantially horizontal support for the socket, an upwardly opening, opaque pocket forming member carried by and secured to the support and extending horizontally from the end thereof and of a configuration to receive and fit closely about a horizontally disposed lamp socket and lamp bulb, a lamp socket in the pocket forming member, a socket carried lamp bulb having a luminous surface, and its light center substantially at the level of the upper edge of the pocket forming member to reflect light upwardly and outwardly, an opaque annular reflecting cover of a diameter such as to cover the pocket forming member and placed

10. closely adjacent the top of the lamp bulb for screening the lamp bulb against observation at normal eye level and reflecting direct and reflected light downwardly and outwardly, and annular screening means of a radius substantially the distance from the base of the socket to the light source and interposed between the edge of the pocket forming member and the edge of the cover for intercepting light emitted by the lamp at angles below the cover.

15. 4. A luminaire such as claimed in claim 3, wherein the socket cover, pocket forming member and the screen are unitary and the cover is detachably supported on the screen.

15. 5. A luminaire such as claimed in claim 3, wherein the upper edge of the pocket forming member is slightly above the light center, and the upper edge of the screening means is slightly above the edge of the pocket forming member and at substantially the level of the bottom of the cover.

20. 6. A luminaire for use below the normal eye level and for illuminating a working plane below the luminaire, comprising a substantially horizontal support for the socket, an upwardly opening, opaque pocket forming member carried by and secured to the support and extending horizontally from the end thereof and of a configuration to receive and fit closely about a horizontally disposed lamp socket and lamp bulb, a lamp socket in the pocket forming member, a socket carried lamp bulb having a luminous surface, and its light center substantially at the level of the upper edge of the pocket forming member to reflect light upwardly and outwardly, an opaque annular reflecting cover of a diameter such as to cover the pocket forming member and placed closely adjacent the top of the lamp bulb for screening the lamp bulb against observation at normal eye level and reflecting direct and reflected light downwardly and outwardly, screening means interposed between the edge of the pocket forming member and the edge of the cover for intercepting light emitted by the lamp at angles below the cover and a pivotal mounting for the socket so that the socket may be lifted up for lamp removal.

25. 35. 40. 45. LEROY C. DOANE.
